UNITED STATES PATENT OFFICE.

HENRY J. MITCHELL, OF CINCINNATI, OHIO.

FARM-GATE.

1,028,588.

Specification of Letters Patent. Patented June 4, 1912.

Application filed December 11, 1908. Serial No. 466,955.

To all whom it may concern:

Be it known that I, HENRY J. MITCHELL, a citizen of the United States, residing at the city of Cincinnati, in the county of 5 Hamilton and State of Ohio, have invented certain new and useful Improvements in Farm-Gates, of which the following is a specification.

The object of my invention is to provide 10 a farm gate which shall be cheap of manufacture, simple in construction and efficient in use.

The main features of my invention are as follows, to wit:—First:—When it is pushed 15 longitudinally to be opened, it is automatically elevated off the ground. Second:—When approximately, its center has been reached in opening, it can be swung to assume a position at right angles to its closed 20 or normal position on a swinging hinge. Third:—It is constructed in such a manner that when open, it will be balanced and hang in perfect equilibrium. Fourth:—It can be locked when closed both against opening and upward shifting or movement. 25 Fifth:—It is provided with an auxiliary gate, which can be opened and closed readily and locked in any open or closed position as desired. Its other features and advantages 30 will readily become apparent from the following specification and claims.

In the accompanying drawing forming part of this specification.—Figure 1 is a view in elevation of my gate in position, looking 35 at it from one side, say the rear side. Fig. 2 is a view in elevation of my gate in position looking at it from the other side, say the front side. Fig. 3 is a view of my gate in elevation looking toward it in an open 40 position, and Fig. 4 is a plan view (detached) of the swinging hinge and elevating roller.

The gate is supported between two gate supporting posts or standards 1—2.

45 The gate is made up of a series of bars, slats or boards 3 arranged one above the other, some extending across the entire width of the gate and others approximately half way; they may however be arranged in 50 any manner and form. These slats are supported and held together by cross pieces or strips 4 attached at each side of the slats 3 at both ends and near its center. I may use as many of these cross strips 4 as I desire. 55 Midway, between the cross strips 4 and extending up from the bottom of the gate half

its height, I provide short cross pieces 5. These cross pieces strengthen the gate and keep it in alinement. These various slats and cross pieces can be arranged and spaced 60 as desired. One of the slats 3 is peculiarly formed, having an inclined or tapered bottom edge 6. On the inner end of this slat 3 with the inclined bottom edge 6, I place a guide or lock block 7.

On the gate supporting post 2, I attach in any suitable manner, preferably by bolt and nut connection, a bracket or strap hinge composed of leaves 8 having eyes 9 to which the loop or strap 10 is loosely attached by means of pins 12. This loop or strap 10 at its lower end carries a roller or wheel 14 mounted loosely on a pin 15. This bracket or strap hinge just described swings in and out on the post 2, and the peculiar shaped 75 slat 3 with the inclined edge 6 works through the slot or space 16 in said bracket hinge. When the gate is shoved forward or backward and when closed the lock block 7 fits in said slot or space 16, locking and supporting 80 the gate at said end.

On the post 1, I attach a finger or curved pin 17 which passes between the cross pieces 4 at that end of the gate adjacent to said post 1 and prevents any lateral play of the 85 gate, a hook 18 (see Fig. 1) can be dropped forward over one of the slats 3 and locks the gate against any upward or other movement.

When it is desired to open the gate, the operator unhooks the hook 18, then pushes 90 the gate longitudinally in direction of arrow, this forces the inclined edge 6 to travel over the roller 15 and as the inclined edge 6 passes over said roller 15, it elevates the gate off the ground on account of the increasing degree of inclination on edge 6, so that when the center cross piece 4 is reached, the entire gate is elevated and hangs in suspension on the bracket hinge; the gate is then swung around, still held by the loop 100 10 of the bracket hinge, said loop 10 turning around with the gate on the hinges or leaves 8, until the gate stands at right angles to its former normal or closed position, the center cross pieces 4 (see especially Fig. 3 105 when the gate is open) being on one side of the post, as they are purposely placed out of the middle line of the gate so as to balance it when open as shown. The gate is opened only half way and then swung open. To 110 close the gate it is swung back and slid in place until the lock block 7 is in loop 10

and the pin 17 between cross end pieces 4 and the hook 18 passes over one of the slats and then the gate is locked against any displacement.

5 I will now describe the auxiliary gate. This auxiliary gate is formed of two slats 21 connected at the ends by end pieces 22. This auxiliary gate is supported and slides between the cross pieces 4 and 5 at that end 10 of the gate where it is situated. A lever 23 fulcrumed at 24 to slat 3 and at 25 to lower slat 21 of the auxiliary gate is the means whereby the auxiliary gate is moved in and out of position. Moving the lever 23 15 forward and backward moves the auxiliary gate forward and backward or in other words opens and shuts it. A chain 26 carrying at its end a pin 27 is attached to the lever 23. In one of the slats 3, I provide 20 holes 28 and I provide holes as 29 in lever 23. When the auxiliary gate is opened and it is desired to lock it at a definite point the pin 27 is placed in the holes 29 in lever 23 and in hole 28 in slat 3 and thus the gate is 25 held against inward or outward movement. Holes as 30 (see Fig. 1) may also be placed in the auxiliary gate slat 21 so that the fulcrumed point 25 of the lever 23 can be varied if desired.

30 This gate is especially desirable between the fields or subdivisions of a farm, but can be used as an entrance gate to the farm itself. It can be readily operated, works easily and smoothly, does not get out of 35 order or alignment under even extraordinary circumstances and can be hung in place by any one; no skill being required.

The auxiliary gate can be opened and small stock or fowl driven through it, the 40 other stock being held in check by the large gate.

The gate may be made of wood or iron, wood being preferred.

Any of the parts which wear may be made 45 of heavier material and reinforced if desired.

I do not wish to confine myself to the specific construction shown and described, but may deviate from such construction and arrangement of parts.

50

What I claim as new and of my invention and desire to secure by Letters Patent is:—

1. In a gate of the character described, a post, a bracket hinge fitted to said post and adapted to swing thereon, said bracket hinge composed of a hinge, a loop, and a roller combined together, a gate, said gate supported by said bracket hinge, and adapted to slide and swing, one of the slats which compose the body of the gate provided with a horizontally inclined lower edge, whereby by sliding the gate longitudinally, by reason of the inclined edge of the slat passing over the said roller, it at the same time receives a rising movement and a lock block 60 attached to said gate, which enters the bracket hinge when the gate is closed, to lock said gate, as set forth.

2. In a gate of the character described, a post, a bracket hinge fitted to said post, 70 and adapted to swing thereon, said bracket hinge composed of a hinge which is connected to the post, a loop, which carries at its lower end a wheel, said wheel revolving in said loop, the loop and wheel swinging 75 on said hinge, a gate, said gate supported by said bracket hinge and adapted to slide and to swing, one of the slats which compose the body of the gate provided with a horizontally inclined lower edge, whereby, 80 by sliding the gate longitudinally, by reason of the inclined edge of the slat passing over the said wheel, it at the same time, receives a rising movement, and a lock block attached to said gate which enters the 85 bracket hinge when the gate is closed to lock the gate, as set forth.

Cincinnati, Ohio, Nov. 23rd, 1908.

HENRY J. MITCHELL.
